H. J. EDWARDS.
BAFFLE PLATE FOR V-TYPE MOTORS.
APPLICATION FILED SEPT. 13, 1918.

1,416,803.

Patented May 23, 1922.

UNITED STATES PATENT OFFICE.

HENRY J. EDWARDS, OF ELYRIA, OHIO, ASSIGNOR TO THE WILLYS-OVERLAND COMPANY, OF TOLEDO, OHIO, A CORPORATION OF OHIO.

BAFFLE PLATE FOR V-TYPE MOTORS.

1,416,803.

Specification of Letters Patent. Patented May 23, 1922.

Application filed September 13, 1918. Serial No. 253,898.

To all whom it may concern:

Be it known that I, HENRY J. EDWARDS, a subject of the King of Great Britain and Ireland, residing at Elyria, county of Lorain, and State of Ohio, have invented certain new and useful Improvements in Baffle Plates for V-Type Motors, of which I declare the following to be a full, clear, and exact description.

10 This invention relates to internal combustion engines and has for its object to provide means to control the amount of oil delivered to the engine cylinder or the surface within which the piston operates. Although not limited thereto, the invention has particular utility in connection with V-type motors in which the cylinders are located at an angle, in which position not only is more oil received, being thrown, splashed 15 or carried up by the rotating elements of the engine than in the case of an upright cylinder, but the inclination of the cylinders also tends to retard the return flow of any excessive oil into the crank casing. It 20 is to be understood, however, that the controlling means employed herein may be used with vertically arranged cylinders, as well as with V-type motors.

By my invention I provide means operating to deflect a portion of the oil which would otherwise enter the cylinder, it being also an object of my invention to so arrange such means as to permit the oil received by the surface within which the piston works 35 to drain back into the casing. It is apparent that such means may be supported and carried into the proper place by any suitable mechanical expedients.

Further objects of this invention relate to 40 the details of construction, arrangement of parts, and the association of the elements disclosed herein as illustrating one means for carrying the invention into effect.

Referring to the drawings, Figure I is a 45 sectional view of a V-type Knight motor with my invention connected therewith.

Figure II is a section through a portion of a V-type motor with poppet valves showing my invention applied thereto.

50 Figure III is a bottom plan view of the type of baffle plate illustrated herein as one efficient means effective for the purposes herein intended.

Figure IV is a sectional view on the line IV—IV of Figure III.

55

Referring to Figure I, there is shown within the crank casing 10 the usual crank shaft 11 connected to the piston rod 12 by the assembly 13, the lower portion of the crank shaft casing 10 being provided with an oil pan 15 adapted to contain oil to a sufficient level so that the rotation of the crank shaft effects a splashing of the oil up into the engine cylinders to lubricate the engaging surfaces between the engine piston and the cylinder within which the same operates.

In Figure I the piston 20 is shown within the inner sleeve or movable cylinder 21 of the well-known type of a sliding sleeve valve motor, and interposed between the sleeve 21 which constitutes a moving cylinder for the piston 20 and the rotating crank shaft 11 is located any type of baffle means 23 for deflecting a portion of the oil delivered thereto.

The baffle 23 may be supported from any 75 desired portion of the engine construction. I have found that a convenient location of support for the baffle 23 is on the lower end of the sleeve or cylinder 21. The baffle 23 in the particular embodiment shown herein 80 consists in a plurality of plates 25 and 26, each provided with elongated slots 27 and 28, each slot having an enlarged portion 29 and narrow portion 29'. The lower end of the sleeve or cylinder 21 is provided with a plurality of studs 30, one for each of the slots 27 and 28 of each of the plates. The studs 30 85 may have a hexagonal central portion 31 to facilitate the application of a wrench in screwing the same into the end of the cylinder 21, a reduced neck portion 32 and an outer head 33. The heads 33 of each of the studs 30 are of a size to pass through the enlarged end 29 of the openings 27 and 28 when the baffle is inserted thereon, while the 90 reduced portion 32 slides in the narrow portions of the slots 29' with the heads 33 of the studs overlapping the lower surface of the baffle plates 25 and 26, to thus support the baffle on the studs in spaced relation from the 95 end of the cylinder or sleeve 21.

Suitable means for locking the baffle plates in position may be employed, and to this end there is shown herein a leaf spring 35, located and terminating in such position as to 105 engage the vertical side wall of the stud

heads 33 when the baffle plates 25 and 26 have been inserted on the studs and slid endwise to cause the reduced portion 32 of the stud 30 to enter the narrow portions 5 of the slots 27 and 28. It is apparent that any other means for securing the baffle plates 25 and 26 to any desired portion of the engine structure may be used.

The baffle plate sections 25 and 26 are 10 spaced apart to provide an opening 36 therebetween within which the piston rod operates, and through which the oil which it is desired to deliver into the cylinder may be thrown on the cylinder wall surface, the 15 baffle plates operating to deflect a portion of the total amount of oil thrown centrifugally from the rotating crank shaft 11. The relative area of the lower end of the cylinder or sleeve 21 left open for the passage of oil, 20 may be readily determined and the baffle plates 25 and 26 may then be made of the proper size and secured to the cylinder a proper distance apart.

As shown in Figure II, the baffling means 25 23 may be secured to a portion of the inner surface of the crank casing 10, or the lower end of the cylinder 21.

The operation of my invention will be 30 readily understood from the foregoing. It will be seen that there is provided means to control the amount of oil delivered to the surface within which the piston moves by interposing a baffle to deflect a portion of the oil delivered to the cylinder by a rotating element splashing the same up from the oil pan. A portion of the baffling means extends on both the side of approach and the side of departure of the rotating crank shaft 11 relative to the cylinder sleeve 21 35 and the location of the same on either side may be controlled at will, if desired, to meet the needs of the engine.

It is to be understood that this invention comprehends broadly the provision of any 45 means for controlling the amount of lubricating oil thrown up into the cylinder of an internal combustion engine by interposing means to deflect a portion of the oil so delivered and that the location of the baffle or deflecting means is immaterial, it being evident that the same may be supported from any desired portion of the engine construction. It is also to be understood that any 50 type of baffle may be employed, and, moreover, that any means for securing the same in the structure in contact with or spaced from the cylinder of the engine may be employed.

Having thus described my invention, what 60 I claim as new and desire to secure by Letters Patent, is:—

1. In an internal combustion engine, the combination with an open ended cylinder of means secured thereto for deflecting oil delivered to said cylinder including a readily

removable baffle plate provided with a plurality of pin receiving openings, a plurality of pins carried by said cylinder, and locking means for securing said baffle to said pins.

2. In an internal combustion engine, the 70 combination with an open ended cylinder of means secured thereto for deflecting oil delivered to said cylinder including a plurality of studs projecting from the end of said cylinder, a baffle plate provided with slots 75 having an enlarged end, said studs having heads adapted to pass through the enlarged ends of said slots, and a reduced portion for passing into the other portion of said slots, and means to lock said baffle plates to said 80 studs when in position.

3. In an internal combustion engine, the combination with an open ended cylinder of means secured thereto for deflecting oil delivered to said cylinder including a plurality 85 of studs projecting from the end of said cylinder, a baffle plate provided with slots having an enlarged end, said studs having heads adapted to pass through the enlarged ends of said slots, and a reduced portion for 90 passing into the other portion of said slots, and a leaf spring carried by said baffle, the free end thereof extending over the enlarged portion of said slots and adapted to engage the edge of a stud when in the narrow portion 95 of said slot.

4. A device of the class described comprising an open ended cylinder, a stud projecting from the open end of said cylinder, and a baffle plate secured upon said stud in 100 spaced relation with respect to the cylinder, the portion of the stud between the plate and cylinder being adapted to receive a suitable tool for turning the stud.

5. A device of the class described comprising an open ended cylinder, a stud projecting from the open end of said cylinder, a baffle plate secured upon said stud, and yieldable means for removably holding said baffle plate upon said stud.

6. A device of the class described comprising an open ended cylinder, studs projecting from the open end of said cylinder, and a baffle detachably secured upon the studs, said baffle comprising a plurality of spaced apart 115 plates.

7. A device of the class described comprising an open ended cylinder, studs projecting from the open end of the cylinder, a baffle comprising a plurality of spaced apart 120 plates removably mounted upon said studs, and yieldable means secured upon the plates and engaging the heads of the studs for locking said plates thereon.

8. In an internal combustion engine, the 125 combination of an open ended reciprocally mounted cylinder, a crank shaft operatively connected with said cylinder for reciprocating the same, a piston movable in said cylinder, a connecting rod extending through the 130

open end of the cylinder and connecting the piston with said crank shaft, and a baffle plate secured upon the open end of the cylinder and movable therewith during reciprocation of the same.

9. In an internal combustion engine, the combination of an open ended reciprocally mounted sleeve and a piston therein, of means for actuating each relatively to the other, and a baffle secured upon said sleeve and movable therewith for deflecting oil delivered to the sleeve.

10. In an internal combustion engine, the combination of an open ended reciprocally mounted sleeve and a piston therein, of means for actuating each relatively to the other, and a pair of spaced baffle plates secured upon the open end of said sleeve and movable therewith for deflecting oil delivered to the sleeve.

11. A device of the class described comprising an open ended cylinder, and a baffle

comprising spaced apart plates secured upon and in spaced relation with respect to the open end of the cylinder, the outer edges of 25 the plates being approximately within the confines of the outer circumference of the cylinder.

12. In an internal combustion engine, the combination of an open ended cylinder, a 30 piston movable in the cylinder and provided with a connecting rod, and a baffle comprising a plurality of spaced apart plates secured on the open end of the cylinder, the said connecting rod reciprocating between 35 the plates.

13. In an internal combustion engine, the combination of an open ended cylinder, a baffle reciprocally mounted and in spaced relation to said cylinder, and means for reciprocating said baffle.

In testimony whereof, I affix my signature.

HENRY J. EDWARDS.
